ATTORNEY

UNITED STATES PATENT OFFICE.

DALTON K. WILSON, OF WATERLOO, IOWA.

MANURE-SPREADER.

No. 903,123.

Specification of Letters Patent.

Patented Nov. 3, 1908.

Application filed January 21, 1908. Serial No. 411,931.

To all whom it may concern:

Be it known that I, DALTON K. WILSON, a citizen of the United States of America, and a resident of Waterloo, Blackhawk county, Iowa, have invented certain new and useful Improvements in Manure-Spreaders, of which the following is a specification.

My invention relates to improvements in manure spreaders, and the object of my improvements is to provide new and convenient means for driving the conveyer apron, and for keeping up a proper adjusted engagement between the driving and holding pawls and the driving ratchet-wheel. This object I have accomplished by the means which are hereinafter fully described and claimed, and which are illustrated in the drawings hereto annexed, in which:—

Figure 1 is a side elevation of the wagon-box of a manure spreader, equipped with my improved mechanism for driving the conveyer-apron, and Fig. 2 is an enlarged detail upper plan view of the driving pawl and its prolongations.

Similar numbers refer to similar parts throughout the several views.

The wagon-box 28 contains a movable conveyer-apron 35, driven by sprockets 34 on a transverse shaft 21 in the usual manner, and passing about an idler 36 at the front of the box.

Brackets 30 are secured to the rear part of said box, havings bearings for the ends of the shaft 7 of the beater-drum 1. A cam-wheel 8 is secured to the end of the shaft 7 and a ratchet-wheel 22 to the end of the shaft 21 on same side of the box. Between said cam-wheel and said ratchet-wheel are certain driving connections and pawls described as follows:

An angular arm 4 is pivotally suspended on a stud 3 extending laterally from the upper projection 2 of the bracket 30, the lower end of the said arm having a pivotal connection 9 with the rear member 10 of the driving-pawl 18. This driving-pawl 18 is a cross-piece joining the forward ends of the parallel forks 33 and 37 of the rear member 10, the parallel portions passing on either side of the ratchet-wheel 22. An anti-friction wheel 5 is rotatably mounted on a stud 6 projecting inward from the angle of the arm 4, and its concave edge is adapted to be contacted with by the convex edge of the cam-wheel 8. The numeral 32 designates an arm which is curved upwardly from the

member 10. A stud 15 extends laterally from the forward upper portion of the bracket 30, and on this stud are pivoted two bell-crank levers, the outer one having an upper member 13 and a lower member 17, while the inner lever has an upper member 14 and a lower member 16.

A lug 19 extends outward from the outer side of the fork-member 37, and lies in the path of movement of the lower end of the member 17 of the outer bell-crank lever.

The upper end of the upper member 13 of the same lever is perforated from front to rear to receive the connecting-rod 23, the forward end of the latter being pivotally connected to a hand-lever 24 whose lower end is pivoted on a stud 26 extending from a plate 27 secured to the forward part of the side of the wagon-box 28. The rear end of the connecting-rod 23 is passed through a staple 12 extending from the box 28. A clip or open boxing 11 has its ends slidably secured about the rear end of the rod 23, one end on either side of the staple 12, and a spiral spring 31 secured about said rod between the forward end of said boxing and the said staple 12.

The upper end of the upper member 14 of the inner bell-crank lever is connected with the upper end of the projecting member 32 of the driving-pawl body by means of a tension-spring 29. The lower end of the lower member 16 of said inner lever is pivotally connected to a double-ended guard or holding-pawl 20, the detents of the latter being so suspended over the ratchet-wheel teeth, that when one detent is in full engagement with a tooth of said ratchet-wheel, the other detent is spaced away from the root of the contacting teeth to the extent of a space of one-half a tooth.

In operation, the rotating cam-wheel 8 imparts by its driving contact with the anti-friction wheel 5, a reciprocating motion to the swinging-arm 4 and its connected driving-pawl body 10. The cross-bar pawl 18 thus contacts with and drives the teeth of the ratchet-wheel 22 around.

The resilient connection 29 between the members 14 of the inner bell-crank lever and the member 32 of the driving-pawl body, keeps either one or the other of the detents of the suspended holding-pawl 20 in full engagement with the teeth of the ratchet-wheel 22, whether the said driving-pawl be in its forward or back position, and affords

compensation when the cross-bar has become lessened in width by wear so that said bar is kept in contact with the ratchet wheel for operative engagement notwithstanding such wear.

When the hand lever 24 is shifted in one direction in its rack 38, the rear end of the connecting-rod 23 exercises a yielding pull upon the member 13 of the outer bell-crank lever, due to the inclosed spring 31. The moving forward of the member 13 causes a rearward movement of the member 17, causing the latter to contact with and push back the lug 19 on the side-bar 37 of the driving-pawl body thus restricting the throw of the pawl 18, and decreasing the speed of rotation of the ratchet-wheel 22 and the conveyer-chain 35. When the hand-lever is moved in the other direction, by the same intermediate means the lower member 17 is drawn forward, permitting the driving-pawl to have a longer stroke, thus increasing the speed of movement of the conveyer-apron. As the pawl 18 is limited in its stroke by the above means, so that when at its shortest stroke it is pushed farthest back, the anti-friction wheel 5 is swung back enough so that it is contacted at each revolution by only a small part of the edge of the angular part of the cam-wheel 8, the latter exercising but a short driving stroke, which at the extreme is less than a tooth's width on the ratchet-wheel, causing cessation of motion to said wheel.

Having described my invention, what I claim as new, and desire to secure by Letters Patent, is:

1. In a manure spreader, in combination, a wagon-box, a movable conveyer-apron therein, a rotatable shaft, a cam-wheel secured to said shaft, a ratchet-wheel adapted to drive said movable apron, a swinging arm adapted to be contacted by said cam-wheel, a driving-pawl pivotally connected to said swinging arm and adapted to engage said ratchet-wheel, said driving-pawl having a laterally extending lug, and means adjustably interposed in the path of movement of said lug adapted to limit the length of stroke of said driving-pawl.

2. In a manure-spreader, in combination, a wagon-box, a movable conveyer-apron therein, a rotatable shaft, a cam-wheel secured to said shaft, a ratchet-wheel adapted to drive said conveyer-apron, a swinging arm adapted to be contacted by said cam-

wheel, a driving-pawl pivotally connected to said swinging-arm and adapted to engage said ratchet-wheel, said driving-pawl having a laterally extending lug and an upwardly extending arm, means adjustably interposed in the path of movement of said lug adapted to limit the length of stroke of said driving-pawl, a bell-crank lever whose upper end has a resilient connection with the upwardly extending arm of said driving-pawl, and a holding-pawl medially and pivotally suspended from the lower member of said bell-crank lever, said holding-pawl having a detent at each end, such detents so engaged with the teeth of said ratchet-wheel that whenever one detent engages the root of a tooth the other detent engages another tooth to a distance of one-half the length of the latter.

3. In a manure spreader, in combination, a wagon-box, a movable conveyer-apron therein, a rotatable shaft, a cam-wheel secured to said shaft, a ratchet-wheel adapted to drive said movable conveyer-apron, a swinging arm, said swinging arm adapted to be contacted by said cam-wheel, a driving-pawl pivotally connected to said swinging arm and adapted to engage said ratchet-wheel, said driving-pawl having a laterally extending lug, and resilient means adjustably interposed in the path of movement of said lug adapted to limit the length of stroke of said driving-pawl.

4. In a manure spreader, in combination, a wagon-box, a movable conveyer-apron therein, a rotatable shaft, a cam-wheel secured to said shaft, a ratchet-wheel adapted to drive said conveyer-apron, a swinging arm, an anti-friction wheel pivoted to said swinging arm and adapted to be contacted by said cam-wheel, a holding-pawl adapted to engage said ratchet-wheel, a driving-pawl pivotally connected to said swinging arm and adapted to engage said ratchet-wheel, said driving-pawl having a laterally extending lug, and means adjustably interposed in the path of movement of said lug adapted to limit the length of stroke of said driving-pawl.

Signed at Waterloo, Iowa, this 31st day of Dec. 1907.

DALTON K. WILSON.
